Primary Examiner—M. N. Pandozzi

(74) Attorney, Agent, or Firm—Michael G. Crilly, Esq.

(57) **CLAIM**

The ornamental design for a soda fountain appliance for residential use, as shown and described.

DESCRIPTION

FIG. 1 is a top, front, and right side perspective view of a soda fountain appliance for residential use showing my new design;

FIG. 2 is a front elevational view thereof;

FIG. 3 is a right side elevational thereof, the left side elevational view being a mirror image thereof;

FIG. 4 is a top plan view thereof; and,

FIG. 5 is a rear elevational thereof.
